United States Patent Office

Des. 228,678
Patented Oct. 16, 1973

228,678

SPECTACLE FRONT

Jack Bloch, Leominster, and Vitalino Marchi, Concord, Mass., assignors to Foster Grant Co. Inc., Leominster, Mass.

Filed June 26, 1972, Ser. No. 266,006

Term of patent 14 years

Int. Cl. D16—06

U.S. Cl. D57—1 F

FIG. 1

FIG. 2

FIG. 3

FIG. 4

FIG. 1 is a front elevational view of a spectacle front showing our new design,

FIG. 2 is a plan view thereof,

FIG. 3 is a side elevational view thereof, and

FIG. 4 is a sectional view taken along the line 4—4 of FIG. 1.

We claim:

The ornamental design for a spectacle front, substantially as shown.
